UNITED STATES PATENT OFFICE.

THEODOR R. WILLWERSCHEID, OF ST. PAUL, MINNESOTA.

LAMP-SOCKET.

1,075,318.

Specification of Letters Patent.

Patented Oct. 7, 1913.

Application filed September 27, 1911. Serial No. 651,631.

To all whom it may concern:

Be it known that I, THEODOR R. WILLWERSCHEID, a citizen of the United States, residing at St. Paul, in the county of Ramsey and State of Minnesota, have invented 5 a new and useful Improvement in Lamp-Sockets, of which the following is a specification.

My invention relates to improvements in 10 lamp sockets particularly those used in connection with housings or outdoor signs.

My socket is adapted to be mounted in such a way that the electric conductors connecting with it are separated from the inner 15 closing housing and letter plate, thus preventing short circuiting from moisture and the wearing away of insulation.

Among the objects of my invention is to provide a socket without separable body 20 parts which will permit the removal of the letter plate without loosening the socket or cutting wires and at the same time forming a waterproof joint with the housing.

The particular advantage of my device is 25 its simplicity of operation and cheapness of construction together with efficient action.

In the drawings with which I have illustrated my device and which form part of this specification, Figure 1 is a perspective 30 view of my improved socket showing the housing partly broken away Fig. 2 is a sectional elevation of a lamp and socket mounted in the housing, and Fig. 3 is a view of another form of housing fastener.

35 In the above drawings I have illustrated an incandescent lamp A mounted in a socket B carried by a mounting C which is attached to a housing D. The housing D is formed of two parts 2 and 3 forming the back or support and front or letter plate of an electric sign as ordinarily constructed. Each of 40 these parts has a rim portion 4 around its outer edge, the rim 4 of the front fitting over the rim of the back 2 and forming a close joint therewith. The front and back 45 housings are fastened together by means of bolts 5 having thumb nuts 6 on the front of the housing. Any similar suitable fastening may be substituted for the bolts 5 which are especially designed to be accessible from the 50 front of the housing.

In Fig. 3 I have shown a separator 30 attached to the back of the housing D and supporting the letter plate 32 which is fastened to the separator by a thumb screw 33 on the front of the housing. The rims 34

and 35 are shown connected by bolt 36 in the figure. The housing illustrated is of the simplest form and may be constructed to fit any design of electric lighted display desired, the essential feature of the design being the front housing or cover piece 3 fitting over the back 2 and removable without disturbing the back on the electrical parts.

The mount or spider C consists of a flat 65 strap as illustrated in Fig. 1 having a body portion 26 resting on the back 2 of the housing and fastened thereto by a rivet 7 or in any other suitable manner and having arms 8 extending forward from the body for the 70 support of the socket B. The mount C is illustrated with only two arms 8 but may be provided with three or more for the proper support of the socket. By the use of a mount C the socket is raised from the supporting back 2 which is frequently formed of sheet metal, thus separating the electrical conductors connected with the socket from the housing. The spider C also serves to prevent any moisture remaining between the 75 socket B and the back 2 and allows a free circulation of air between the same which will tend to keep the socket B dry and prevent the decay or rusting of the back 2.

The socket B is formed of porcelain, hard 80 rubber or other suitable insulating material, with a body part 9 of cylindrical or conical form in one piece and with an attachment base 10. The base 10 has laterally extending lugs 11 on opposite sides of the 85 body 9 adapted to receive screws or bolts 12 connecting the base with the mount C at the extremities of the arms 8. Lugs 13 are formed on the base in the usual manner for the attachment of electrical conductors 14 90 supplying electrical energy to the lamp A in the usual manner. The mount C is so proportioned that the conductors 14 resting on the base 10 of the socket B are substantially equally spaced between the front and back parts of the housing D thus giving the greatest safety from short circuiting. The body 9 of the socket extends through the front of the housing and is formed with the usual lamp receptacle 15 for the reception 95 of an incandescent lamp as illustrated in Fig. 2.

Immediately within the front 3 the body 9 is provided with a shoulder 16 fitting the housing snugly and beveled back from the 100 housing with a curved cross-section to the body. The shoulder 16 extending around

the body 9 in contact with the front 3 serves as a support for the front which is pressed against the shoulder by the action of the bolt 5. The shoulder 16 with its curved 5 cross-section also serves as a drip flange to gather moisture which may penetrate the housing D between the front 3 and the shoulder 16 and also any moisture which may gather on the inner face of the front 10 and to convey it from the body 9 downward to its lowest point 17 where it may flow onto the inner face of the front 3 and to the bottom of the housing. The moisture accumulating in this manner is thus directed 15 away from the base 10 and its attached conductors.

The body B is formed immediately in front of the shoulder 16 with a substantially cylindrical surface 18 which is adapted to 20 fit the opening in the front 3 of the housing D. The surface 18 has a height substantially equal to the thickness of the material of the front 3. Immediately in front of the surface 18 the body 9 is formed with a 25 groove 19 and a drip flange 20 adjacent to the lamp A. Both the groove and flange are circular in cross-section and the flange is of less diameter than the surface 18 permitting the free removal of the front 3 from the 30 housing without disturbing the socket B. The formation of the groove 19 adjacent to the surface 18 directs moisture flowing down on the outside of the front 3 away from the joint between the front and socket on its 35 upper side and causing it to flow around the socket in the groove 19 to its lower side. The convex surface of the drip ring 20 is adapted to receive moisture resting on the lamp A and direct it downward to the lower 40 part of the ring where it drains out onto the lip of the ring and drops off.

It will be readily seen that the moisture gathering on any part of the lamp or socket is directed by the peculiar formation of the 45 flanges and grooves of the socket to a point below the main body part 9 of the socket where it accumulates and drips thus freeing the socket from moisture. This action is secured without the use of a part adjustable 50 able against the outside of front 3 to close the joint between the front and socket and permitting the free removal of the front without the removal of any such adjustable

part and securing a substantially watertight socket in a single piece.

55

In accordance with the patent statutes I have described the principles of operation of my invention together with the apparatus which I now consider to represent the best embodiment thereof but I desire to have it understood that the construction shown is only illustrative and that the invention can be carried out by other means and applied to uses other than those above set forth within the scope of the following claims.

65

Having described my invention, what I claim as new and desire to protect by Letters Patent is:

1. A support for an incandescent lamp, comprising in combination, a housing formed in two coöperating parts, a socket within said housing mounted on one of said parts by a spider having an opening between the same and said socket to prevent moisture from collecting between the base of said socket and said housing, said socket extending through the other of said parts for the reception of a lamp, and having a shoulder within said second housing part tapering away from said socket to form an uninterrupted thin edge adjacent the inner wall of said second housing part to close the aperture therein and adapted to gather moisture therefrom and direct it away from said socket and lamp.

85

2. In a support for an incandescent lamp, comprising, a housing formed in two parts, a spider like socket mount attached within said housing to one of its parts and having arms extending toward the other of its parts, a lamp socket detachably secured to the arms of said mount and extending through the other housing part for the reception of a lamp, and electric conductors for the lighting of said lamp attached to the base of said socket and being spaced by said mount away from the housing parts thereby preventing short circuiting in said housing by moisture.

95

In testimony whereof, I have signed my name to this specification, in the presence of two subscribing witnesses.

THEODOR R. WILLWERSHEID.
